UNITED STATES PATENT OFFICE

116,822

DESIGN FOR A TAPE

Charles A. Horton and John C. Dinsmore, Providence, R. I., assignors to Hope Webbing Company, a corporation of Rhode Island

Application June 2, 1939, Serial No. 85,302

Term of patent 14 years

To all whom it may concern:

Be it known that we, Charles A. Horton and John C. Dinsmore, citizens of the United States of America, residing at Providence, county of Providence, State of Rhode Island, have invented a new, original, and ornamental Design for a Tape, of which the following is a specification, reference being had to the accompanying drawing, forming a part thereof.

The figure is a plan view on an enlarged scale showing a portion of a strip of tape.

We claim:

The ornamental design for a tape, substantially as shown.

CHAS. A. HORTON.
JOHN C. DINSMORE.
